UNITED STATES PATENT OFFICE.

ARTHUR H. PITNEY, OF STAMFORD, CONNECTICUT, ASSIGNOR TO POSTAGE METERS & MACHINES COMPANY, OF STAMFORD, CONNECTICUT, A CORPORATION OF DELAWARE.

ENVELOPE-SEALING DEVICE FOR POSTAGE METERS.

Application filed October 12, 1922. Serial No. 594,153.

To all whom it may concern:

Be it known that I, ARTHUR H. PITNEY, a citizen of the United States, residing at Stamford, in the county of Fairfield and State of Connecticut, have invented certain new and useful Improvements in Envelope-Sealing Devices for Postage Meters; and I hereby declare that the following is a full, clear, and exact description thereof, reference being had to the accompanying drawings, which form part of this specification.

This invention is a novel improvement in machines for sealing and stamping envelopes and has particular reference to postage meter machines such as shown and described in my Patent #1,370,668 dated March 8, 1921, and Wheeler's Patent #1,410,859, dated March 28, 1922. In said patented mechanisms the envelopes are automatically fed from a pile on a feed table to devices whereby the flaps are opened, moistened, and sealed, and then passed on through suitable stamping, post marking, canceling, and metering devices, such as shown in the above mentioned Patents #1,370,668 and 1,410,859.

The principal object of the present invention is to enable the sealing mechanism to be adjusted to suit different sizes or heights of envelopes without having to alter the position of any of the parts of the mechanism as such mechanism adjusted to seal envelopes of one size might not properly seal envelopes of another size, but with my present invention the moistening and flap sealing devices can be practically instantly adjusted to suit the size of the envelopes to be sealed.

In the accompanying drawing I have illustrated one practical embodiment of the invention, and will describe the same with reference thereto to enable others familiar with the art to adopt and use the same. In the claims the novel combinations of parts and novel features of the invention for which protection is desired, are summarized.

The accompanying drawing represents a front elevation of part of the sealing mechanism of a postage meter machine with one practical form of my present invention applied thereto.

In the postage meter machine above referred to, the envelopes to be sealed are placed edgewise on a feed table 1, parallel

with a wall 6 against which the envelopes are aligned preparatory to being fed to and past the moistening and sealing mechanisms. 55

Between the feed rollers 7 and 8 and in rear of the wall 6 is a casting 25 which has a water pocket 44 in its upper end, in which is placed a moistening device 50 which may 60 be a brush, or other suitable kind. Water may be supplied to the pocket 44 by a removable inverted container 28, or any other suitable means, brush moistener 50.

Attached to the casting 25 is a guide plate 65 52 which is adapted to guide the horizontally extended flaps of the envelopes, fed forward by the belt 8^a to and over the moistener 50.

Above the guide plate 52 is a plate 54 70 75 which covers the fountain and preferably is hinged to the casting 25 in order to yield to the different thicknesses of various quantities of envelopes, the flaps of which are intended to pass beneath plate 54, the weight 80 of which tends to press the flaps against the moistener 50 as the envelopes move forward by contact with the feed rollers 7 and 8. Also mounted on the casting 25 to the rear side of the plate 54 is a plate 58 which 85 extends from a point adjacent the fountain beyond rollers 9 and 13 to a point adjacent the rollers 10 and 14, and the projecting portion 58^a of plate 58 is curved downward, as indicated, so that it will fold the flap of the 90 envelope, against the body of the envelope after said flap has passed the moistener 50 and the presser bar 19, so that the envelope will be properly sealed by the rollers 9, 10, 13, and 14, when it passes therebetween. The 95 forward edge 54^a of the plate 54 is preferably curled upward as shown so that the flaps of the envelope (passing along the wall 6 and guided into horizontal position by the plate 52) will readily pass under the plate 54 and over the moistener 50. The part 58^a is so curved as to cause the flap to properly fold down before the envelope reaches the rollers 10 and 14.

The casting 25, to which are attached the 100 guides 54 and 58 and the fountain 44, is provided with one or more supporting rods 29 which slide in a suitable stand 30 attached to the feed table 1.

The parts thus far described substantially 105 correspond in construction and operation to

the parts shown in my Patent #1,370,668, and Wheeler Patent #1,410,859, but may be of any other suitable construction.

In order to seal different sizes of envelopes it is necessary to raise or lower the member 25 with all the parts mounted thereon. Heretofore, this adjustment has been accomplished by means of a rack and pinion, and a clamping screw, but this was found 10 to be inconvenient and slow on account of having to find the proper height each time a change was made.

The present invention enables the adjustment to be made quickly and without the 15 use of any gearing and retaining clamp.

The novel attachment as shown comprises a base 1^x, a hand operated lever 2^x, and a sector 3^x. The base 1^x is fastened by screws both to the main table 90 and the feed table 20 1, of the sealing machine.

The sector 3^x is rigidly fastened to the base 1^x. On its outer edge are cut a series of ratchet teeth 3^a which are numbered at intervals for convenience in locating the desired position of the hand lever 2^x. The lever 2^x is pivoted at 1^a to the base 1^x at a point coinciding with the center of the sector 3^x. The lower end of lever 2^x is provided with a toe piece 2^b which may be integral 30 therewith or fastened thereto by screws 2^c.

A thumb latch or dog 4^x is pivoted at 2^a to lever 2^x, and is adapted to engage the teeth 3^a of the sector 3^x. A spring 4^c inserted between dog 4^x and the hand lever 2^x normally forces the tooth of dog 4^x into engagement with the ratchet teeth 3^a.

The operation is as follows:

One of the supporting rods 29 of the sealer 25 rests directly on the toe piece 2^b of lever 40 2^x, consequently if the outer end of lever 2^x is moved downward, the sealer will be raised. The dog 4^x under pressure of spring 4^c will engage the ratchet teeth 3^a of sector 3^x, and prevent the lever 2^x from returning under 45 the weight of the sealer 25, and thus hold the sealer raised or adjusted to the desired height.

When it is desired to lower the sealer, pressure of the thumb on the dog 4^x will disengage it from the ratchet teeth 3^a, and lever 2^x may then be moved in the reverse direction and lower the sealer as desired.

The lever 2^x may be held fast at any position on the arc of the sector 3^x, and when 55 the proper heights for sealing a certain size envelope is determined note may be taken

of the number of the ratchet teeth which the dog 4^x then engages. And reengaging the dog 4^x with such ratchet tooth will insure correct and quick resetting of the sealer for that size of envelope at any time.

What I claim is:

1. In combination with envelope sealing devices of the character specified; a pivoted lever for raising and lowering said sealing devices, and means for securing the lever in adjusted position to hold the sealing devices in any vertically adjusted position.

2. In combination with mechanism for moistening and sealing envelopes, and a vertically movable support therefor; of a pivoted lever having one end engaged with said support, means for adjustably fastening the free end of the lever to hold the support in any vertically adjusted position.

3. In combination with envelope sealing devices of the character specified; a pivoted lever for raising and lowering said sealing devices, a segment beside the lever, and means for securing the lever to the segment to hold the sealing mechanism in any vertically adjusted position.

4. In combination with mechanism for moistening and sealing envelopes, and a vertically movable support therefor; of a pivoted lever having one end engaged with said support, a segment adjacent the free end of the lever, and means on the lever engaging said segment to hold the support in any vertically adjusted position.

5. In envelope sealing mechanism of the character specified having flap folding, moistening and sealing devices; and a vertically adjustable support carrying said devices; a lever for raising and lowering said support a segment beside the lever, and a device on the lever adapted to engage the segment to hold the support in any vertically adjusted position.

6. In combination with means for moistening and sealing envelopes, and a vertically movable support therefor; of an oscillating lever pivoted adjacent the support and having one end engaged with said support; a toothed segment adjacent the other end of the lever; and a dog on the lever adapted to engage said toothed segment to hold the support in any vertically adjusted position.

In testimony that I claim the foregoing as my own, I affix my signature.

ARTHUR H. PITNEY.
